ARTHUR A. BYERLEIN, OF DETROIT, MICHIGAN, ASSIGNOR TO GENERAL MACHINERY CORPORATION, OF HAMILTON, OHIO, A CORPORATION OF DELAWARE

PRESS

Application filed February 1, 1932. Serial No. 590,059.

This invention relates to presses, and more particularly to presses for drawing sheet metal and the like.

One object of the invention is the provision of a drawing press having a press bed in which are arranged upper and lower fluid pressure chambers forming a pressure cushion cooperating with the pressure ring, the movable elements of the upper and lower fluid pressure chambers being connected externally of the chambers for simultaneous movement.

Another object of the invention is the provision of a fluid pressure cushion of the character described having upper and lower cylinder elements and piston elements, the movable parts of the cushion being connected for simultaneous movement in a novel manner, designed to provide for a minimum amount of leakage of pressure fluid from the cushion.

Other objects and advantages of the invention will be apparent from the following description, the appended claims and the accompanying drawing, in which—

Fig. 1 is a front view, partly in section, showing the lower portion of a drawing press embodying the present invention;

Fig. 2 is a vertical section taken centrally through one of the pressure cushions and through the press bed; and

Fig. 3 is a section on the line 3—3 of Fig. 2.

Referring more particularly to the drawing by reference numerals, 10 designates the frame of a press for drawing or forming sheet metal or the like, only the lower portion of which is shown as the top portion may be of any conventional character of the single or double acting type. This frame embodies uprights 11, the lower parts of which form portions of the press bed, which is generally designated by the numeral 12.

On the bed 12 is a bolster plate 14 which supports a lower die 15. Surrounding the lower die 15 is a pressure ring or ejector ring 16, supporting the peripheral edges of the sheet metal blank 17. The pressure ring 16 is supported by a series of pins 18 that project up through holes in the bolster plate, the lower ends of these pins resting on pressure plates provided in the bed of the press. As

herein shown the pressure ring is supported by two fluid pressure cushions horizontally spaced apart and provided in the two wells or openings 20 of the press bed. These cushions contain air or other fluid under pressure. While two pressure cushions have been illustrated, it will be understood that the press may have only one pressure cushion, or three or more pressure cushions may be provided, especially in presses of the larger sizes adapted for operation on very large sheets of metal. These pressure cushions, which have been generally designated by the numeral 21, serve to exert a desired pressure on the pins 18 causing the peripheral portions of the metal plate to be held yieldingly under a predetermined pressure between the pressure ring 16 and the lower side of the upper die, which has not been shown.

In accordance with the present invention, each of the pressure cushions 21 has a plurality of fluid pressure chambers, each chamber being preferably formed by upper and lower telescopically engaged piston and cylinder elements, the movable elements of the cushion being connected together so as to operate in unison in order that the total pressure exerted by the cushion on the pins 18 will be twice the value that would be exerted by a cushion having a single air space or chamber and operating under the same air pressure conditions. The double or multiple arrangement of pressure chambers as herein shown permits the fluid pressure, that is the pounds per square inch pressure exerted in the fluid pressure chambers to be kept comparatively small although great pressures may be exerted on the top pressure plate and on the pressure ring. Moreover in accordance with the novel arrangement as herein set forth, there is a minimum of leakage of the pressure fluid from the pressure cushions as the connection from the top movable element to the lower movable element of the cushion does not extend centrally through either the pressure chamber, but on the contrary is arranged outside the cushion so that there is no packed bearing or joint extending through a cushion wall.

The two pressure chambers of the fluid

pressure cushion illustrated in Figs 2 and 3 are designated generally 23 and 24. The top chamber 23 is formed by the cylinder element 25 and the piston element 26, both of which are generally cup-shaped, having telescopically engaged cylindrical walls one of which preferably carries a suitable packing ring 27 designed to prevent leakage. The top wall of the cylinder element 25 forms the pressure plate 29 on which the pins 18 rest, this pressure plate being guided in the press bed by the guide surfaces 30 that are preferably removably secured in the corners of the press bed and which interfit with notched-out corner portions of the pressure pad so as to support the pressure pad for vertical sliding movement but prevent any lateral movement thereof.

The bottom wall 32 of the piston element 26 is extended out laterally, forming the ledges 33, the outer portions of these ledges being supported by downwardly extending walls 34 that may be made integral with the ledges 33 so that the walls 34 constitute an integral part of the piston element. These walls 34 rest on a cross plate 36 that is secured by bolts 37 to the lower side of the press bed, bolts 38 fixing the walls 34 in place in a rigid and secure manner. By reason of this construction the lower or piston element of the top fluid pressure chamber 23 is supported in fixed position so that as the cylinder element 25 is pushed down, when the pressure ring is forced down, the air or other fluid contained under pressure in the pressure chamber will serve to exert a desired pressure upwardly on the pressure ring returning it upwardly after the top die has been raised away from the completed work.

The lower side of the bottom wall 32 has a flat surface 40 and this surface is normally engaged by the flat top surface of a second pressure pad 41 forming a part of a cylinder element 42 of the lower fluid pressure chamber 24. The cylindrical walls of this cylinder element 42 are telescopically engaged by cylindrical portions of the piston element 45 which has a bottom wall 46 resting on the cross plate 36. Suitable packing as indicated at 47 may be provided to prevent leakage past the telescopically engaged surfaces of the fluid pressure chamber. The upper or movable element of chamber 24 is adapted to be moved by means of pins 49 provided at suitable points spaced laterally from the cushion axis so that they are provided externally of the walls of the fluid pressure chambers. These pins 49 extend freely through holes 50 provided in the ledges 33, the upper ends of the pins being fixed to outwardly extending flanges 51 at the lower ends of the cylinder element 25. The yielding upward force exerted by the lower cushion 24 is thus transmitted through the pins 49 directly up to the pressure pad 29, to which fluid pres-

sure exerted by the upper cushion is also applied. The pad thus transmits the force of both cylinders directly to the pins 18. As the connection between the upper or movable elements of the two fluid pressure chambers does not pass through the chambers, or either one of them, there are no packed joints or movable connections extending through a wall of the cushions and consequently there is a minimum amount of leakage of pressure fluid from the cushions.

It will be understood that the air or other pressure fluid contained in the cushions will be equalized, since both cushions are supplied from a common pipe, and any increase or change of pressure in one chamber will be equalized with the pressure of the other. The compressed air from the building air supply is supplied through a check valve and through a suitable pressure regulating valve to the pipe 53 which transmits it to the cushion at a controlled pressure depending on the particular character of the work to be performed. The check valve prevents back flow of air from the cushions to the supply line when the cushion elements are collapsed or partly collapsed toward one another and the pressure is raised above the normal pressure obtaining when the chambers are of maximum volume. The pipe 53 is connected to a passage 54 provided preferably in a bottom portion of the lower piston element, and a branch pipe 55 extends up to a passage 56 provided in the piston element 26.

In accordance with the described arrangement, it will be apparent that the double fluid pressure cushion is of very simple construction being formed essentially of only a few parts, the arrangement providing for a minimum amount of leakage since there is only the single telescopic connection between the movable elements of a collapsible chamber.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A yielding pressure cushion of the character described comprising cooperating fixed and movable elements forming a top fluid pressure chamber of variable capacity, additional fixed and movable elements forming a lower fluid pressure chamber of variable capacity, a fixed element of one of said pressure chambers being located adjacent a movable element of the other chamber, and a connection between the movable elements of said cushion provided externally of said chambers.
2. A yielding pressure cushion of the char-

acter described comprising cooperating fixed and movable elements forming a top air chamber of variable capacity, additional fixed and movable elements forming a lower air chamber of variable capacity, a fixed element of one of said pressure chambers being located adjacent a movable element of the other chamber, air supply passages for said chambers, and a connection between the movable elements of said cushion provided externally of the fixed element of the top chamber.

3. In a press of the character described, a yielding pressure cushion comprising upper and lower fluid pressure chambers of variable capacity each chamber having a movable element and a stationary element cooperatively associated therewith, a fixed element of one of said pressure chambers being located adjacent a movable element of the other chamber, and means provided externally of said chambers for connecting the movable element of one chamber to the movable element of the other chamber.

4. In a press of the character described, a yielding pressure cushion comprising cooperating fixed and movable elements forming a top fluid pressure chamber of variable capacity, additional fixed and movable elements forming a lower fluid pressure chamber of variable capacity, the fixed element of the top fluid pressure chamber having a bottom surface forming a stop for the upper surface of the movable element of the lower fluid pressure chamber, and means connected to the movable element of the top chamber and extending down into abutting engagement with the upper surface of said lower movable element.

5. In a press of the character described, a yielding pressure cushion comprising telescopically engaged upper and lower piston and cylinder elements providing a top air chamber, supporting means fixing the lower element in the press, additional upper and lower piston and cylinder elements providing a second air chamber below the top air chamber, and a connection from the upper element of the top air chamber extending freely through said supporting means to the upper element of the second air chamber and provided at points spaced from the piston and cylinder axis.

6. In a press of the character described, a press bed, a pressure plate slidably guided in said bed, said plate having a downwardly extending cylindrical wall and constituting a cylinder element, a piston element slidably guided in said wall, supporting means fixing said piston element to said bed and formed as an outward and downward continuation of said piston element, pins fixed to said cylinder element and extending down through openings in said supporting means, a lower cylinder element having an upper surface engaged by said pins and adapted to be moved

with the upper cylinder element, and a lower piston element fixed in said bed in telescopic engagement with said lower cylinder element.

In testimony whereof I hereto affix my signature.

ARTHUR A. BYERLEIN.
